UNITED STATES PATENT OFFICE.

WILLIAM M. HORNBECK, OF PEORIA, ILLINOIS.

AUTOMATIC STOCK-FEEDING MACHINE.

1,311,696.

Specification of Letters Patent. Patented July 29, 1919.

Application filed March 28, 1917. Serial No. 157,917.

To all whom it may concern:

Be it known that I, WILLIAM M. HORNBECK, a citizen of the United States, residing at Peoria, in the county of Peoria and 5 State of Illinois, have invented certain new and useful Improvements in Automatic Stock-Feeding Machines; and I do hereby declare that the following is a full, clear, and exact description of the invention, which 10 will enable others skilled in the art to which it appertains to make and use the same.

This invention relates to new and useful improvements in automatic stock feeders.

An object of the invention is to furnish a 15 stock feeder and a peculiarly formed and peculiarly mounted agitator therefor for moving the material to a position to be reached by the animals.

To the end that my invention may be 20 readily and thoroughly understood, I have provided the accompanying drawing, in which:

Figure 1 shows my machine in perspective. Fig. 2 is a sectional end elevation of the 25 same.

Fig. 3 is a plan of an agitator.

Fig. 4 is a cross section of one of the parts 30 of the agitator taken on line 4-4, Fig. 3, viewed in the direction of the arrow.

Fig. 5 is a cross section of another portion 35 of the same on line 5-5, Fig. 3; and,

Fig. 6 is a cross section of still another part taken on line 6-6, viewed in the direction of the arrow.

The body of the feeder is made up of the 40 ends A and the sides B which, as shown in Figs. 1 and 2, are closer together at their upper portions than at their bases so that the feeder at the bottom will be much greater in area than that at its upper portion. B' represents a top of any suitable or desired 45 form which may be hinged or otherwise attached, or may be removable.

C represents an inner longitudinal wall 50 which may be thicker at its upper end than at the bottom and D D represent transverse walls which, as shown in Fig. 1, in broken lines, are likewise thicker at the top than at the bottom by which any one of the compartments formed thereby will have greater area at the bottom than at the top.

E indicates the bottom of the feeder which 55 preferably slants upward from each wall B toward the middle or beneath the wall C.

Each edge terminates in a portion F slanted

upward at an opposite angle to form a feeding trough G, and H indicates an opening beneath each wall B covered by a slide J vertically adjustable and secured in any desired position, for instance by means of 60 bolts K and wing-nuts L, said bolts being fastened in the wall, for example. The slide may have one or more slots M through which the bolts extend, the said wing-nuts serving to secure the slide in the position 65 desired.

N is a small slide at each end of the feeder to accommodate a small compartment, while the described slide J may be of considerable 70 length and accommodate a large single compartment or several smaller ones, lying between those having said slides N. The arrangement of the slides, however, is unimportant since they are well known structures and no claim is made thereto of them- 75 selves.

My feeder by reason of its being provided with the outwardly and downwardly flaring sides is adapted for feeding hay, alfalfa, or other like material which when more or less 80 compressed, as is well known, will engage the walls by friction, so that it will not readily descend in a compartment whose walls were parallel.

By flaring the walls, however, the material 85 will gradually descend as it is used, aided, of course, by its constant withdrawal through the feed openings H by the animals. When feed of other kinds is used such as oats, oil meal, chop feed, and the like, which 90 may be damp or in such shape at least as to become caked, the fact that the walls all flare outwardly at the bottom will permit the mass in any one compartment to descend into the gradually widening space. 95

I have provided a special agitator, shown 100 in plan in Fig. 3, for use with feed in this condition. It has the form of a skeleton frame having a rounded end O continuing into parallel extensions P connected at their outer ends by a portion Q. Parallel to the extensions P and lying between them is a substantially central extension R pivoted at S upon the bottom E of the machine. Said agitator has an upwardly bent extension T 105 which lies outside the side B and the slide J substantially as shown in Fig. 2. The cross section of the rounded inner end and the extension P is as shown in Fig. 4. That 110 is to say, the outer edges of the mentioned

parts are comparatively thin while the inside edges are somewhat thicker, also the part Q is thin at its inner edge and thick at its outer edge. In its position for use the portion Q lies substantially beneath the slide J.

The extension T lying in position to be operated by the animal in feeding is swung from side to side on its pivot to agitate the feed and work it down into the trough G. The broken lines in Fig. 3 show the positions taken up by the agitator in its extreme positions and it will be clearly understood that since the outer edges within the machine are narrowest they will cut under the caked feed while the inner thicker edges will move the feed over the bottom E, each succeeding movement working the feed closer to the front finally depositing it in the trough at the lowest portion of the inclined bottom. As the feed works down toward the slide and gets behind the thicker outer edge of the portion Q that portion will positively force the feed out to a position where it can be reached by the animal which in feeding will operate it.

This form of agitator in a feeding machine operating with caked feed, oil cake, or condition powder, and the like, has been found to produce most excellent results.

The pivot point S of the agitator is spaced from the center from which the curved extension O is described and lies between the inner and outer ends of the structure so that the said curved extension will have a side-wise swing and cut beneath the material in the same way as the extensions P, the extensions swinging in opposite directions.

Each compartment of the feeding machine, no matter what its size may be, or if there is but one compartment only, when widest at the bottom will permit feed of any nature to easily descend as it is used, and there will be no chance, therefore, for the material to lodge above the agitator and stop moving downward.

I desire to make it clear that it is not my intention to be confined exactly to what is shown and described since various changes may be made in the structures without departing from the spirit and intent of the invention and the scope of the appended claims.

Having thus described my invention, I claim:

1. As an article of manufacture, an agitator for a feeding machine comprising a flat frame arranged to pivot between its ends within the machine upon its floor, said frame being rounded at one of its ends and having substantially straight parallel extensions each projecting from said rounded part outside the wall of said machine, the outer marginal edges of the latter and the parallel extensions being thinner than their

inner edges, the said frame at its end outside the said machine having a portion extending perpendicularly to the plane thereof.

2. As an article of manufacture, an agitator for a feeding machine comprising a flat skeleton-like frame structure arranged to pivot between its ends, one of its ends being rounded and described from a center spaced from the pivoting point of said frame, the rounded end extending into substantially straight parallel portions lying outward from the said pivoting point, the frame at the other end having a portion extending perpendicularly to the plane thereof, the pivot point lying inside the machine, the last described and lying outside the same.

3. As an article of manufacture, an agitator for a feeding machine comprising a flat skeleton-like frame having a rounded portion at one end terminating in spaced extensions lying substantially parallel to one another, and a substantially central portion arranged to be pivotally mounted, the position of the pivot therefor lying between the ends of the frame, the frame at the end opposite the rounded portion having a portion extending perpendicularly to the plane thereof and lying outside the machine, the pivot of the frame lying within said machine.

4. As an article of manufacture, an agitator for a feeding machine comprising a flat skeleton-like frame having a rounded portion at one end terminating in spaced extensions lying substantially parallel to one another, and a substantially central portion arranged to be pivotally mounted, the position of the pivot therefor lying between the ends of the frame and spaced from the center from which the said rounded portion is described, the frame at its end opposite the rounded portion having a portion extending perpendicularly to the plane thereof lying outside the wall of the machine, the pivot of the frame lying inside said wall.

5. As an article of manufacture, an agitator for a feeding machine comprising a flat skeleton-like frame having a rounded portion at one end terminating in spaced extensions lying substantially parallel to one another, and a substantially central portion, said frame also having a portion connecting each spaced extension with the said central portion, the latter being arranged to be pivotally mounted between the said rounded portion and the connecting portions, the frame at its end opposite the rounded portion having a portion extending perpendicularly to the plane thereof lying outside the wall of the machine, the pivot of the frame lying inside said wall.

6. As an article of manufacture, an agitator for a feeding machine comprising a flat skeleton-like frame having a rounded portion at one end terminating in spaced ex-

tensions lying substantially parallel to one another, and a substantially central portion, said frame also having a portion connecting each spaced extension with the said central portion, the latter being arranged to be pivotally mounted between the said rounded portion and the connecting portions, the outermost edges of each of said connecting portions lying at an acute angle to the central portion and its respective spaced extension, the frame at its end opposite the rounded portion having a portion extending perpendicularly to the plane thereof lying outside the wall of the machine, the pivot of the frame lying inside said wall.

7. As an article of manufacture, an agitator for a feeding machine comprising a flat

skeleton-like frame having a rounded portion at one end terminating in spaced extensions lying substantially parallel to one another, and a substantially central portion arranged to be pivotally mounted, the position of the pivot therefor lying between the ends of the frame, said frame having an extension bent in a direction substantially perpendicular to the plane of the frame, lying outside the wall of the machine, the pivot of the frame lying within the latter. 20 25

In testimony whereof I affix my signature in presence of two witnesses.

WILLIAM M. HORNBECK.
